UNITED STATES PATENT OFFICE

156,613

COLLAPSIBLE STAND FOR SCREEN OR THE LIKE

Leo T. Du Mais, Chicago, and John T. Heck, Elmhurst, Ill., assignors to Da-Lite Screen Co., Inc., Chicago, Ill., a corporation of Illinois

Application August 15, 1946, Serial No. 132,552

Term of patent 14 years

(Cl. D61—1)

To all whom it may concern:

Be it known that we, Leo T. Du Mais and John T. Heck, both citizens of the United States, and residents of Chicago, in the county of Cook and State of Illinois, and Elmhurst, in the county of DuPage and State of Illinois, respectively, have invented a new, original, and ornamental Design for a Collapsible Stand for Screen or the Like, of which the following is a specification, reference being had to the accompanying drawing, forming a part thereof.

Fig. 1 is a perspective view of a collapsible stand for screen or the like, showing our new design with the legs extended;

Fig. 2 is a fragmentary perspective view of one of the legs looking in the direction of the arrows 2—2 in Fig. 1;

Fig. 3 is a fragmentary cross sectional view of one of the legs taken on line 3—3 of Fig. 1;

Fig. 4 is an elevational view of the stand with legs collapsed; and

Fig. 5 is a top plan view of the disclosure in Fig. 1.

The essential features of our design are shown in full lines.

We claim:

The ornamental design for a collapsible stand for screen or the like, substantially as shown and described.

LEO T. DU MAIS.
JOHN T. HECK.
